UNITED STATES PATENT OFFICE.

THOMAS M. LYNCH, OF WASHINGTON, DISTRICT OF COLUMBIA.

FISHING-ROD SUPPORT.

965,826.

Specification of Letters Patent. Patented July 26, 1910.

Application filed January 30, 1909. Serial No. 475,178.

To all whom it may concern:

Be it known that I, THOMAS M. LYNCH, a citizen of the United States, residing at Washington, in the District of Columbia, 5 have invented certain new and useful Improvements in Fishing-Rod Supports; and I do hereby declare the following to be a full, clear, and exact description of the invention, such as will enable others skilled in 10 the art to which it appertains to make and use the same.

My invention relates to fishing-rod supports or holders.

It has for its object to provide for a device of this nature which is very simple in construction, cheap to manufacture, and which may be used in a boat or on shore with equal success.

Another object is to permit the changing 20 of the angle at which the rod is held in the support without altering the position of the support itself.

Another object is to avoid danger of the rod becoming disengaged from the holder 25 in case said rod is moved therein accidentally.

Another object is to provide for holding the rod in a nearly upright position for baiting the line.

30 Further objects will become apparent from the following description.

The invention consists broadly of a support comprising a standard adapted to be secured to the gunwale, seat or other part of 35 a boat or to a fixture on shore, a V-shaped fork at the upper end of said standard, substantially horizontal portions extending substantially parallel to each other from the ends of said fork, and an inverted V-shaped 40 fork connecting the other extremities of said horizontal portions.

The invention also consists in the features of construction and combinations of parts 45 hereinbefore described and specified in the claims.

In the accompanying drawing illustrating the preferred embodiments of my invention: Figure 1 is a perspective view of the support. Fig. 2 is a side view showing it attached to the gunwale of a boat and a fishing-rod arranged in said support, a second position of the rod being shown in dotted lines. Fig. 3 is a side view of the support mounted on a block anchored to the ground, 55 a fishing-rod being shown in the holder with its bottom end arranged in a socket in said

block, so that said rod is supported substantially vertically as when it is desired to bait the line. Figs. 4 and 5 are detailed views of the anchoring pin and block respectively, 60 and Fig. 6 is a front elevation of the support showing the tubular coverings of the forks in section and the lower end of the prong of the lower fork spaced away from the standard for the purpose hereinafter explained. 65

Referring more particularly to the drawing, 1 designates the standard which is preferably screw-threaded at its lower end, as at 2, for connection with a fixture.

3 and 4 designate the prongs of the V-shaped fork, 5 and 6, the horizontal portions and 7 and 8, the prongs of the inverted V-shaped fork. The latter fork is preferably arranged in a plane substantially parallel with the plane of the first mentioned 75 fork. The end of the prong 4 of the V-shaped fork is spaced away from the upper end of the standard, as at 9, to permit the tubular coverings 10 to be slipped on and removed when worn. As shown, each of 80 the prongs of both forks is covered by one of these tubes preferably made of rubber to prevent chafing of the handle of the fishing-rod.

The support or holder is preferably made 85 of a single bent metal rod. A sufficient length of the rod is left straight at one end to constitute the standard. It is then bent laterally at an oblique angle to form the prong 3 of the lower fork, thence bent rearwardly to form the horizontal portion 5, thence bent laterally upwardly and then downwardly to form the prongs of the upper fork, thence bent forward forming the horizontal portion 6, and finally bent laterally and downwardly to form the prong 4 of the lower fork.

In Figs. 3, 4 and 5, I have illustrated how the support may be used on shore. Said holder is attached to a block 11 by having its 100 standard screwed into an opening 12 in the upper surface near one end of the block. Said block is also provided with a socket 13 into which the butt end of the handle of the fishing-rod is adapted to fit, as hereinbefore 105 explained. The block may be anchored to the ground in any suitable manner. I have shown one way of doing this which consists of a pin 14 screwed into the end of the block and extending down a sufficient distance into 110 the ground. The pin is preferably bent, as shown, being secured to the end of the block

and having a horizontal portion 14^a extending in line with the longitudinal axis of said block whereby the tendency of the fishing rod to turn the block over endwise and pull 5 the pin out of the ground is reduced by reason of the lever arm, of which the horizontal portion of the pin is a part, being lengthened thereby.

It will be noted that by reason of the construction which I employ, the rod may be 10 adjusted at different angles, the angle when the extreme tapered end of the handle is engaged with the holder being different from that when the enlarged middle portion of said 15 handle is arranged in the support. It will also be seen that the horizontal portions prevent the rod from being jarred or otherwise inadvertently displaced from the holder. As 20 the support is made of a single piece of bent metal rod, it can be very quickly formed into shape and manufactured very cheaply.

The holder may be turned at will by reason of the screw connection of its standard with a part of a boat or with the block 11 so 25 that it will extend in any desired direction. When the support is attached to block and anchored by the pin 14, the block may be turned on said pin to obtain this adjustment.

I claim:

30 1. A fishing rod support made of a single metal rod comprising a standard, an upright fork at the upper end of said standard, horizontal portions extending substantially parallel to each other from the ends of said 35 fork, and an inverted fork connecting the other extremities of said horizontal portions, said forks and horizontal portions being formed by suitably bending the rod from the top of the standard and bringing the

end of said rod back adjacent thereto where it forms one prong of the upright fork. 40

2. A fishing-rod support made of a single metal rod comprising a standard, an upright fork at the upper end of said standard, horizontal portions extending substantially 45 parallel to each other from the ends of said fork, and an inverted fork connecting the other extremities of said horizontal portions, said forks and horizontal portions being formed by suitably bending the rod from the 50 top of the standard and bringing the end of said rod back adjacent thereto where it forms one prong of the upright fork, said last mentioned end of the rod being spaced away from the standard, and tubular coverings arranged on the prongs of said forks and adapted to be put on and taken off at 55 said end of the rod by reason of it being spaced away from the standard.

3. The combination, with a block having 60 a socket therein, and means to anchor said block to the ground, of a fishing-rod support comprising a standard secured to said block, a fork at the upper end of said standard, horizontal portions extending substantially 65 parallel to each other from the ends of said fork toward the socket in said block, and an inverted fork connecting the other extremities of said horizontal portions, whereby a fishing-rod may be arranged substantially vertically in said support with its 70 butt-end in the socket in the block.

In testimony whereof, I affix my signature, in presence of two witnesses.

THOMAS M. LYNCH.
